UNITED STATES PATENT OFFICE.

ELMER C. SCHACHT, OF TROY, NEW YORK, ASSIGNOR TO PEERLESS SURFACING MACHINE CO. INC., OF TROY, NEW YORK, A CORPORATION OF NEW YORK.

DISK SANDING MECHANISM.

Application filed March 1, 1926. Serial No. 91,426.

Reference may be had to the accompanying drawings, and the reference characters marked thereon, which form a part of this specification. Similar characters refer to 5 similar parts in the several figures therein.

The principal objects of the invention are to simplify the construction, and reduce the cost of disk sanding mechanisms.

Other objects will appear in connection 10 with the following description.

Fig. 1 of the drawings is a face view of a disk sanding head embodying my invention with portions of the device partly broken away.

15 Fig. 2 is a view in perspective of the clamp plate whereby the abrasive disk is secured to its rotatory support.

Fig. 3 is a view in perspective of a broken away central portion of the supporting metal 20 disk and hub forming part of the rotatory support for the abrasive disk showing the sink or well to receive the clamping plate.

Fig. 4 is a face view of a partly broken away abrasive disk adapted for use in the 25 construction shown in Fig. 1.

Fig. 5 is a central cross section of the head taken on the broken line 5—5 in Fig. 1.

Referring to Figs. 1, 2, 3, 4 and 5, the disk sanding head includes a supporting disk, 1, 30 mounted upon a hub, 2; and an abrasive disk, 3, mounted upon the supporting disk.

The supporting disk, 1, is preferably made of flexible resilient metal, as sheet steel, and is preferably faced with a flexible sheet or 35 body, 4, of yielding material such as soft vulcanized rubber, or preferably rubberized fabric similar to that of which rubber belting is made.

This facing or covering, 4, is preferably 40 secured upon the face of the disk, 1, by means of rivets, 5; and if desired it may be of greater or smaller diameter than the disk, 1, as shown.

The hub, 2, is secured upon the back of 45 the supporting disk, 1, by means of rivets, 6, and is formed with a central sink or well, 8, opposite a similarly shaped opening, 9, formed in the disk, 1, which sink or well is adapted to receive a clamping plate, 10, 50 whereby the abrasive disk, 3, is secured to the supporting body formed by the sheet metal disk, 1, and the facing, 4.

The hub, 2, is also provided with a central 55 aperture, 11, adapted to receive the end of a shaft, 12; and the clamping plate, 10, is

provided with a central aperture, 13, adapted to receive a screw, 14, whereby the clamping plate is secured to said shaft, 12, causing the disk sanding head to rotate with said shaft.

The abrasive disk, 3, may be made of sand 60 paper, emery paper, emery cloth or the like of a grade and character adapted for the intended work.

The abrasive disk is preferably cut in the form shown in Fig. 4, with a central aperture, 14, to receive the screw, 4, with four radial slits, 18, extending outwardly from the central aperture, 14, and with a plurality of apertures, 15, on opposite sides of said central aperture, 14, adapted to receive pins, 16, 70 projecting from the inner side of the clamp plate, 10, which pins are adapted to enter similarly located openings, 17, in the bottom of the sink or well, 8.

The disk, 3, is thus provided with four 75 floating tongues which converge toward the center of the disk and which are adapted to yield to the pressure of the clamp plate, 10, and be forced into and tightly fit within the well, 8, in the hub as the clamp plate, 80 10, is drawn tightly within said well by means of the screw, 4, with the abrasive disk mounted on the face of the supporting disk, 1, with said floating tongues interposed between the clamp plate, 10, and the bottom of 85 the well, 8.

The facing sheet or covering, 4, is formed with a central opening, 7, corresponding in form and size with the well, 8.

In Fig. 3, I have shown the well, 8, rectangular in form with outwardly flaring side walls and the clamp plate, 10, of similar form with its sides, 20, similarly flared outwardly and adapted to fit within the well with the central portion of an abrasive disk, 3, interposed between the walls of the clamp plate and the walls of the well.

The neighboring slits, 18, are formed at an angle of forty-five degrees to each other and the apertures, 15, are so located that when 100 the pins, 16, on the clamp plate are inserted therethrough and into the openings, 17, in the well the slits will extend approximately to the apices of the respective corners or angles of the well.

The tongues formed by the slits, 18, will 105 thus be bent by the clamp plate, 10, into the well along approximately straight lines extending along the bases of the respective tongues, as shown in Fig. 1.

By constructing and clamping the disk in the manner described, the disks can be supplied to the trade in flat form, and without other preparation of the central portion of 5 the disk than the cutting of the slits, 18, and the apertures, 14, and 15.

The shaft, 12, is rotatively mounted in a housing, 21, and has on its inner end a beveled gear, 22, in engagement with a beveled 10 gear, 23, on the inner end of a flexible shaft, 24, which is also rotatively mounted in said housing.

The housing, 21, has a handle, 25, whereby 15 the operation of the abrasive disk upon the work can be controlled.

The operation of the device is as follows:

The abrasive disk, 3, having been mounted upon the supporting sheet metal disk, 1, in the manner above described is rapidly rotated by means of the flexible shaft, 25, beveled gears, 23, and 24, and shaft, 12, while the head is held by the operator with more or less of the abrasive disk, 3, in engagement with the work to be abraded or polished.

25 By reason of the flexible resilient character of the supporting disk, 1, and flexible character of the facing, 4, the operator can by inclining or tipping the disk and by varying the pressure upon the work cause a zone of 30 the abrasive surface of the disk, 3, of greater or less width to engage the surface being operated upon, and can cause the abrasive disk to engage said surface with more or less pressure as desired.

35 The gage, flexibility and resiliency of the sheet metal forming the supporting disk, 1, may be varied in accordance with the nature of the work to be performed; and the facing, 4, may be varied in thickness or diameter, or 40 omitted, as desired.

What I claim as new and desire to secure by Letters Patent is—

1. In an apparatus of the character described, the combination of a support including a hub provided in an end face with a depression or well of polygonal form in a plane transverse to the hub axis, an initially flat abrasive disk provided with a central aperture and a series of slits extending radially from said aperture, one for each angle of the polygon, a clamping plate conforming in shape to the cross-sectional form of the well in the hub of the support, and means for connecting said plate and hub, including a member extending through the central aperture in the disk and adapted to draw the plate into said well, the portions of the disk separated by said slits being thereby drawn into the hub well and clamped between the side walls of the latter and the plate, relative rotation between the disk and support being positively prevented by the shape of the clamping plate and well. 45 50 55

2. In an apparatus of the character described, the combination of a support including a hub provided in an end face with a depression or well of rectangular form in a plane transverse to the hub axis, an initially flat flexible disk provided with a central aperture and four slits extending radially therefrom, a rectangular clamping plate of an area to extend into the well in the hub of the support, and means for connecting said plate and hub including a member extending through the central aperture in the disk and adapted to draw the plate into the wall, the slits in the disk corresponding to the diagonals of the well and the portions of the disk separated by said slits being clamped between the side walls of the well and the plate. 60 65 70 75 80

In testimony whereof, I have hereunto set my hand this 18th day of February, 1926.

ELMER C. SCHACHT.
